UNITED STATES PATENT OFFICE.

VERNON H. YARNALL, OF NEW YORK, N. Y.

CONDUIT.

SPECIFICATION forming part of Letters Patent No. 695,594, dated March 18, 1902.

Application filed December 10, 1901. Serial No. 85,341. (No model.)

To all whom it may concern:

Be it known that I, VERNON H. YARNALL, a citizen of the United States, residing in the borough of Manhattan, city of New York, State of New York, have invented a certain new and useful Improvement in Conduits, of which the following is a description.

The object of my invention is to produce a clay conduit for electric conductors which will afford a better protection for the cables, the sections of which conduit can be maintained in alinement and which will also be well adapted for the junction of conduits of a greater and less number of ducts and at different angles, while preserving the substantial continuity of the surfaces of the ducts at the joints of the sections.

In the accompanying drawings, Figure 1 is a perspective view showing one end of a four-duct conduit-section with one of the alining-keys in position. Fig. 2 is a side elevation showing the joining of two two-duct conduits with a four-duct conduit and the changing of the angle of one of the smaller conduits, the ends of the conduits being shown cut off at an angle to illustrate the partitions. Fig. 3 is an edge view of one of the alining-keys. Figs. 4, 5, and 6 are end views of conduit-sections having, respectively, two, three, and six ducts, the location of keys in both the vertical and horizontal key-spaces being shown in Fig. 6.

A is the clay conduit-section, preferably of general rectangular form and containing two or more ducts B. The intervening partitions between the ducts are formed of two longitudinal walls a b, having an intermediate rectangular air-space c, and in the case of a conduit-section having four or more ducts in different horizontal and vertical planes the crossing walls of the intervening partitions are also separated by a central opening d. The width of an intervening partition, including the two walls and the intermediate space, is the width of two of the outer walls of the conduit or slightly wider, so that in joining sections having a smaller number of ducts with a section having a larger number of ducts, as illustrated in Fig. 2, the substan-

tial continuity of the surfaces of the ducts 50 can be maintained at the joints.

The provision of intervening partitions made of two walls and an intermediate space is advantageous, not only for the reason just stated but for the further reason that the cables in one duct are better protected against injury from the burning out of a cable in an adjoining duct on account of the additional width of the separation between the ducts and also the presence of the intermediate air-space, and, still further, by the making of these partitions with double walls and an intermediate air-space a uniform shrinkage in firing the clay is secured, which would not be the case if the partitions were solid and had 65 the entire thickness of the two walls and the intermediate air-space. The oblong air-spaces in the partitions separating the ducts of the conduit also permit the employment of keys C, having an oblong cross-section, 70 which may be provided with spacing-pins e and which are inserted in these air-spaces of the adjoining sections of the conduit and serve to keep the sections in alinement. One or more of these keys will be employed at 75 each joint, preferably two or more where the conduit-sections have two or more of such spaces, and in the case of a four-duct or six-duct conduit having ducts in different horizontal and vertical planes keys are preferably inserted both in one or more of the horizontal intermediate air-spaces and in one or more of the vertical intermediate air-spaces, so as to prevent any tendency of one section to turn upon another. These keys C may be made 85 of cement, metal, or other refractory material or of wood treated so as to be fireproof or moisture-proof, or both. They are preferably made of a non-conducting material, and the considerable size of the key which is permitted 90 by these intermediate air-spaces enables the keys to be made large enough to give the requisite strength even when made of a non-conducting material. Since the key-spaces extend the entire length of the partitions separating the ducts and the flat keys fill these 95 spaces, such keys act effectively as separators to cut off communication between adjoining

duets at the joints of the conduit-sections, and particularly to prevent the passage of an arc through the joints from one duct to another. To accomplish this result most effectively, the keys should be used in all the key-spaces, as shown in Fig. 6, so as to separate all the ducts from one another at the joints.

What I claim is—

1. A clay conduit-section having a plurality of ducts and provided with partitions separating the ducts, which are formed of two walls and an intermediate air-space, substantially as set forth.

2. A clay conduit-section having a plurality of ducts in different horizontal and vertical planes and provided with partitions separating the ducts composed of two walls and an intermediate air-space, and an additional longitudinal opening at the intersection of crossing partitions, substantially as set forth.

3. The combination with adjoining clay conduit-sections having intermediate oblong spaces in the partitions separating the ducts, of a key oblong in cross-section entering these spaces in the adjoining sections for maintaining the alinement of the sections, substantially as set forth.

4. The combination with adjoining clay conduit-sections having a plurality of ducts located at different horizontal and vertical planes and provided with intermediate oblong spaces in the vertical and horizontal partitions separating the ducts, of keys oblong in

cross-section inserted both in the horizontal and vertical partition-spaces, substantially as set forth.

5. The combination with adjoining clay conduit-sections having oblong key-spaces in their ends, of alining-keys of oblong cross-section made of insulating material, substantially as set forth.

6. The combination with adjoining clay conduit-sections having a plurality of ducts and oblong spaces in the partitions separating the ducts extending the entire length of such partitions, of separators inserted in these spaces and crossing the joints between sections to cut off communication between the ducts at the joints, substantially as set forth.

7. A clay conduit-section, having a plurality of ducts and provided with partitions separating the ducts, such partitions having a thickness double that of the outside walls of the conduit-section, substantially as set forth.

8. A clay conduit-section, having a plurality of ducts and provided with hollow partitions separating the ducts, such partitions having a thickness double that of the outside walls of the conduit-section, substantially as set forth.

This specification signed and witnessed this 9th day of December, 1901.

VERNON H. YARNALL.
